SAIL BATTEN

Roland William Sayers, 46 Harris St., Sans Souci,
New South Wales 2219, Australia

Filed July 9, 1975, Ser. No. 594,233

Term of patent 14 years

Int. Cl. D12—06

U.S. Cl. D12—155

FIG. 1 is a perspective view of a sail batten according to my design;
FIG. 2 is a side elevation of the design;
FIG. 3 is a plan view thereof;
FIG. 4 is an obverse end view thereof; and
FIG. 5 is a reverse end view thereof.

I claim:
The ornamental design for a sail batten, substantially as shown and described.
